CARRIER TRAY FOR FLATWARE

Robert A. Eckersberg, Chicago, Ill., assignor to Ekco Products Company, Chicago, Ill., a corporation of Delaware

Filed Feb. 8, 1961, Ser. No. 63,873

Term of patent 14 years

(Cl. D44—29)

Fig. 1

Fig. 2

Fig. 3

Fig. 4

Fig. 5Fig. 6Fig. 7Fig. 8FIG. 1 is a top plan view of a carrier tray for flatware showing my new design.

FIG. 2 is a side elevation showing the tray as it appears when viewed from the lower edge of FIG. 1.

FIG. 3 is a similar view showing the tray as it appears when viewed from the top edge of FIG. 1.

FIG. 4 is a cross sectional view taken on line 4-4 of FIG. 1.

FIG. 5 is a bottom plan view.

FIG. 6 is an end elevation of the tray as it appears when viewed from the left hand side of FIG. 5.

FIG. 7 is an end elevation of the tray as it appears when viewed from the right hand side of FIG. 5.

FIG. 8 is a cross sectional view taken on line 8-8 of FIG. 1.

I claim:

The ornamental design for a carrier tray for flatware, as shown.
